UNITED STATES PATENT OFFICE.

GUSTAV S. BOESCH, OF DANBURY, CONNECTICUT.

HAT-SIZING MACHINE.

Application filed December 27, 1923. Serial No. 682,862.

This invention relates to hat felting or hat sizing machines.

One of the objects of this invention is to provide a simple but thoroughly practical construction for machines of the above-mentioned character and one that will be rugged, durable, and well adapted to meet the requirements of hard practical use. Another object is to provide a hat sizing machine that will be of thoroughly uniform action, and of such construction and arrangement that uniformity of action, not only throughout the varying requirements of practical use, but also throughout long continued periods of practical use, will be effectively and inexpensively achieved. Another object of this invention is to provide an apparatus of the above character of simple yet thoroughly dependable manual control and capable of effective manual actuation with minimum effort or attention on the part of the operator. Another object of this invention is to provide a sizing machine capable of effective and uniform sizing or felting action; another object is to provide a sizing machine capable of sizing colored or dyed materials for hats. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawings, in which is shown one of various possible embodiments of this invention,

Figure 1 is a front elevation of a sizing machine, certain parts being omitted or broken away to show more clearly certain features of construction,

Figure 2 is a side view of the apparatus as seen from the right-hand end of Figure 1.

Figure 3 is a sectional view of a preferred form of part of the holding mechanism,

Figure 4 is a fragmentary view of a portion of the bearing construction and more particularly as seen along the line 4-4 of Figure 2,

Figure 5 is a sectional view on an enlarged scale as seen on the line 5-5 of Figure 2,

Figure 6 is a sectional view on an enlarged scale as seen on the line 6-6 of Figure 5, and

Figure 7 is a sectional view on an enlarged scale taken on the line 7-7 of Figure 1.

Figure 8 is a detached view on an enlarged scale showing the construction and mounting of the stop as well as of the spring supporting arm associated with one of the rolls, and

Figure 9 is a fragmentary elevation, partly in section, of a modified form of roll construction.

Figure 10 is a fragmentary view of a roll construction.

Similar reference characters refer to similar parts throughout the several views of the drawings.

Referring now to the drawings and more particularly to Figures 1 and 2, there are shown two spaced frame members or standards 10 and 11, suitably held rigidly in spaced relation to form a supporting frame work for the operative mechanisms, the lower portions of these standards being broken away. Adjacent the forward upper portions of the standards 10 and 11, or at the left-hand end thereof, as viewed in Figure 2, these standards are formed or shaped to provide a substantially semi-circularly shaped recess, as at 12 in Figure 2, each recess adapted to accommodate a bearing housing generally indicated at 13 and provided with oppositely disposed and substantially horizontally extending ears or lugs 14 and 15 adapted to rest upon the upper face of the standards 10 and 11. Thus in Figure 1 is shown the bearing housing 13 associated with the standard 11 and another bearing housing 16 of substantially similar construction associated with the standard 10. The bearing housings support, by a bearing construction to be more clearly hereinafter described, a shaft 17 supporting for rotation therewith and intermediate of the standards 10 and 11, a sizing roll, the construction of which will be more clearly described hereinafter.

Each of the ears 14 and 15 associated with the bearing housings is provided with a slot 18, more clearly shown in Figure 4, whence it will be noted that the shape of this slot 18 is preferably substantially oval. A cap-screw 19 passes through the slot 18 in each ear and is threaded into the standard with which the bearing housing is associated, in order that the housing with its associated bearing may be rigidly held in position with respect to the standard. At this point it might be noted that the recess 12 in the standard 11, and

for example, is of sufficient expanse to accommodate loosely therein the bearing housing 13 and that by means of the shape of the slot in the ears, coacting with the cap-screw 19, the bearing housing and the shaft supported thereby may be adjustably positioned with respect to the supporting standard or standards and with respect to the remaining parts of the apparatus.

10 Adjacent the rear upper portion of the standards 10 and 11, or at the right-hand end thereof as seen in Figure 2, each standard is similarly recessed as at 20 to receive and support adjustably a bearing housing, one of which is shown in Figure 2 at 21, and adapted to support rotatably therein a shaft 22 which carries one of the several rolls of the apparatus. The bearing housings in which the shaft 22, of what may be termed the rear roll, is supported, are of substantially similar construction as the bearing housing 13 hereinbefore described, and are secured to the standards in substantially similar manner. The shafts of the rolls thus directly supported by the main frame or standards 10 and 11 may thus be readily brought into proper alignment one with the other, thus insuring the alignment not only of the respective rolls carried thereby, but also of the coacting driving connections between the shafts. Moreover, it will be noted that the bearing housings, in which their associated shafts and respective felting rolls are supported, may be readily disconnected from the main frame of the machine, as for example, by removing the cap-screws 19 which clamp the housings to the main frame.

Referring still to Figures 2 and 1 of the drawings, it will be noted that the shaft 17 supports a sizing roll generally indicated at 23 and that the shaft 22 supports a coacting sizing roll generally indicated at 24. Either one of these shafts may be driven in any suitable manner as by a pulley (not shown) for example from any suitable source of power, and preferably the shaft 17 is thus made the main driving shaft. At its left-hand end as viewed in Figure 1, the shaft 17 carries a sprocket 25 which connects with, and drives a sprocket 26, rigidly mounted on the shaft 22, through a connecting driving chain 27, these parts being diagrammatically indicated in Figure 2. The rolls 23 and 24, the preferred construction of which will be hereinafter detailed, upon rotation form together a trough-like support in which the material to be felted may be placed and rotated and operated upon for felting action. The felt hat bodies are preferably rolled up, several at a time, in a suitable cloth preliminarily to being placed in the felting machine. These hat bodies, it may at this point be noted, are in general of a conical shape or form, and when flattened out and rolled together, form a bundle which is peculiarly

non-uniform and irregular. This bundle is adapted to be acted upon by the rolls 23 and 24 hereinbefore generally identified and by a third roll, generally indicated at 28, this roll 28 being adapted to be brought into proximity to the remaining rolls for conjoint coaction thereof upon the bundle of hats.

Considering now the mounting of the roll 28, it will be noted that the roll 28 is supported upon a driving shaft 29 which in turn is supported for rotation in a pair of transversely spaced frame members 30 and 31 (see Figure 1). These frame members 30 and 31 are preferably associated with the main frame 10-11 so as to be pivoted with respect thereto, thus to permit the roll 28 to be variably positioned with respect to the remaining coacting rolls. The auxiliary spaced frame members 30 and 31 are, moreover, preferably pivoted to move about the axis 85 which is coincident with the axis of the shaft 22 of the roll 24, as will be clear from Figure 2. For this purpose, the lower ends of the members 30 and 31 are sleeved transversely thereof as shown at 32 in Figure 5, 90 in connection with the member 31, and this sleeved portion 32 is in rotatable engagement with a sleeve-like extension 33 of the bearing housing 21 in which the shaft 22 is rotatably supported. This construction is 95 clearly shown in Figure 5 in connection with the member 31, and it will be understood that the member 30 is similarly related at its lower end to the parts of the apparatus at the other end of the shaft 22. The spaced members 30 and 31 are rigidly connected together, so as to form a rigid movable frame member, as by the transversely extending plate member 34 (see Figures 1 and 2) which is preferably securely bolted at its respective ends to the spaced members 30 and 31. 100

One outer end of the shaft 22 carries a sprocket 35 (see Figure 1) which is connected as by means of the chain 36 to a sprocket 37 rigidly mounted upon the left-hand end of the shaft 29, in order thus to transmit the desired rotary movement to the roll 28. As will be clear from Figure 2, the rigidly connected spaced members 30 and 31 may thus be freely moved to carry the roll 28 110 toward or away from its coacting rolls while maintaining the driving connection to the roll 28 throughout its various relative movements. Moreover, it may also, at this point, be noted that in pivotally mounting the frame carrying the roll 28 upon the bearing housings 21 (in which the shaft 22 is supported) there is assured not only a rapid and convenient assembly of the apparatus, but also a rapid disassembly of the parts. 115

Considering now more specifically the supporting of the shaft 29 in the auxiliary movable frame, it will be noted that the shaft 29 is rotatably supported in bearing housings 38 of substantially similar construction. 120

as that of the bearing housings hereinbefore described in connection with the shafts 17 and 22 of the rolls 23 and 28 respectively, excepting that the bearing housings 38 are provided with radially extending lugs or ears 39 (see Figure 2) which serve to hold the housings 38 in connection with the spaced members 30 and 31 by means of suitable bolts or cap-screws 40, the latter passing through slots in the ears 39 of a general oval shape, as hereinbefore described in connection with Figure 4. There is thus provided a capacity for adjustably positioning each bearing housing 38 at the respective ends of the shaft 29, in order that the latter with its associated roll 28 may be properly aligned with the remaining and coacting rolls of the apparatus. It may be pointed out that for uniformity of felting or sizing action, the pressures applied to the bundle of hats between the rolls should be substantially uniformly distributed throughout the material operated upon, and that by the above described construction the proper alignment of the coacting rolls with subsequent uniformity of action may be readily achieved, or irregularity of action of the apparatus readily corrected.

As hereinabove noted, the bundle of hats operated upon is peculiarly irregular in shape and may well be said to be not only of non-uniform thickness throughout its length, but also of non-uniform thickness or diameter through any plane taken transversely about its axis of rotation when placed between the plurality of rolls. The effect upon the movable roll of this peculiarity is a reaction thereupon which results in tending to warp or twist the movable frame in such manner as to bring the shaft 29 of the roll 28 out of alignment with the remaining rolls, and results in an uneven wear upon the shaft 29, as well as upon the bearings supporting this shaft. This effect in practice is of such material extent that defective action of the apparatus soon results, and the defect thus produced in the shaft or shafts results in the discarding not only of the shaft itself, but also of the roll with which the shaft, in the usual forms, is intimately associated. This wearing away of the shaft is, furthermore, greatly enhanced by the fact that the apparatus is operated normally in an atmosphere of steam, while the material operated upon and hence the rolls and the entire apparatus are operated with a plentiful supply of water at high temperature. A vat 90, lined preferably with a non-absorbent material, such as sheet-metal, as at 91 for holding a supply of hot water is supported underneath the rolls by the main frame 10-11, and into this vat the hats operated upon are periodically dipped as will be well understood by those skilled in the art.

To eliminate the above-mentioned and other defects and disadvantages is one of the dominant aims of this invention, and as contributing to the attainment of this object, this invention aims fully to protect the shaft 29 of the roll 28 against the peculiarly and recurrently non-uniform reactions in the following manner. And as conducive to greater durability and ruggedness throughout, particularly in view of the fact that the apparatus operates in an atmosphere largely of steam and inclusive also of various chemicals and the like with which the hot water in the vat is treated, these features of this invention are embodied also in connection with the supporting of the shafts of the remaining rolls with which the movable roll 28 coacts, and hence the preferred embodiment of these features of this invention may be described by reference to Figure 5 of the drawings in which is shown in section the bearing construction employed in connection with the shaft 22 of the roll 24.

Turning now to Figure 5 of the drawings, there is shown at 41 a metallic end or hub member for the roll which is supported upon the shaft 22 and rotates therewith. The sleeved portion 33 of the bearing housing 21 is bored out to a somewhat greater diameter than that of the shaft 22 and receives therein a bushing 42 closely fitting the shaft 22 and formed of any suitable non-corrosive bearing material, such as bronze, for example. The bushing 42 extends inwardly into the main portion of the housing 21 which is bored out as at 21^a to snugly receive the outer race 43 of a ball bearing, the inner race 44 of which abuts against the bushing 42. Externally of the bearing housing 21, the shaft 22 carries a collar 45 secured thereto against relative movement therebetween as by means of a pin 46. Intermediate of the collar 45 and the inner race 44 is positioned a collar 47 which is free to move with respect to the shaft 22. The collar 45 has threaded through it a suitable number of screws 48 adapted to abut against the collar 47 and to urge the latter with the inner race 44 and the bushing 42 against the metal hub member 41 of the roll on the shaft 22. The collar 47 thus securely clamps the inner race 44 and the bushing 42 against the hub 41, thus insuring the rotation of these parts with the shaft and their proper coaction with their respective coacting bearing surfaces, as the outer race 43 and the inner bearing surface of the sleeve-like extension 33. A cap 49 of annular shape is fitted over the end of the bearing housing 21 and secured thereto as by screws 50, it being noted that the cap member 49 may be suitably formed, as at 49^a, as clearly shown in Figure 5, to assist in holding the outer race 43 against a suitably formed annular shoul-

der 21^b at the inner portion of the bearing housing 21.

It will be noted that the bearing housing is thus substantially enclosed, and is preferably well packed with grease or some suitable lubricant, the latter acting to prevent the ingress of moisture or water vapor to the active parts of the bearing. It will also be noted that the shaft 22 is nowhere subjected to wear, the ball-bearing being primarily effective to take up the thrusts imposed upon the shaft, and the bushing 42, coacting with the relatively long bearing surface of the sleeve-like extension 33 of the housing 21 acting to prevent ingress of moisture or water vapor from the other or inside end of the bearing construction. It may also be pointed out that the bushing 42 may be readily removed so that in case of substantial wear thereon a new bushing may be substituted.

The roll on the shaft may be rigidly secured thereto in any suitable manner, as for example, by means of the set-screw 41^a associated with the hub member 41 (see Figure 5). Inasmuch as the bearing support for the other end of the shaft of the roll is of like construction as hereinbefore described, the roll may be rigidly clamped through the bushings and inner races of the bearing construction at its respective ends and thus held rigidly upon the shaft. The adjusting screws in the collars 48 (see also Figure 1) may thus serve to clamp effectively, in rigid assembled relation, all of the several parts mounted upon the shaft and interposed therebetween.

As hereinabove noted, this bearing construction, while of primary importance in connection with the upper or movable roll 28, because of the peculiarly and non-uniform reactions to which this roll is subjected, is preferably embodied in the supporting bearings for the remaining rolls.

Considering now the construction of the rolls, it may be pointed out that in so far as certain features of this invention are concerned, these rolls may be of any suitable construction and may, for example, take the form of the usual wooden cylinders provided with suitable projections, made of wood or other material. Where the rolls are constructed of wood, I prefer to make each roll preferably of two sections, as shown in Figure 9, wherein the roll generally indicated at 51 is made up of the two sections 51^a and 51^b, each substantially semi-circular in cross section. These two sections of the roll 51 are undercut at their respective ends as at 51^c and are held together by means of an end-cap 52 having overlapping flanges 52^a and a hub portion 52^b, by means of which the roll may be secured to the shaft. Suitable wood-screws 52^c pass through the end-cap 52 and into the respec-

tive sections of the roll 51 to hold the parts against relative axial movement. The end-cap 52 forms with the reduced end of the roll sections 51^a and 51^b a driving fit, thus securely holding the parts together and insuring a positive drive of the roll from the shaft through the end-cap itself.

Considering now the preferred construction for the rolls, it might first be pointed out that, in the various processes which a hat in the course of its manufacture undergoes, it is the usual practice to dye the hats after they have been sized or felted. As will be well understood, the fibers of the hat body, after sizing or felting, are very closely, solidly and thoroughly interlocked or inter-felted, and thus the resultant hat body is one which, as to its texture, is so solid that a thorough penetration of the dyes is brought about with difficulty and with the expenditure of great intervals of time. The dyeing, however, may be much more readily and more efficiently and effectively brought about if the hat bodies are dyed prior to the felting or shrinking or sizing operation. Prior to the sizing, the texture of the hat bodies is soft and loose and the fibers are merely sufficiently interlocked to maintain the integrity of structure of the hat body. In this condition the dye may uniformly and thoroughly penetrate and affect all of the fibers throughout the relatively slight thickness of the material, and the dyeing operation may be achieved in much shorter time.

In order that the advantages of dyeing the hat bodies prior to the shrinking or felting operation may be achieved, the felting apparatus must be capable of uniform felting action in order that uniformity of color in the shrunken hat body be achieved and also the sizing apparatus must be unaffected by the dye itself in order that variously colored hat bodies may be successively and indiscriminately operated upon. I prefer, therefore, to make the rolls proper of the apparatus of metal, and in Figure 5 of the drawings is shown fragmentarily and in cross section a hollow substantially cylindrical roll 53 provided with integrally formed end sections 53^a which are suitably bored out to receive the supporting shaft, as the shaft 22. The roll proper 53 may be made of a suitable non-corrosive metal, such as aluminum, for example, and its end portion 53^a is under-cut as at 53^b to be received, with a driving fit into the annular flanged portion 41^b of the hub member 41, the latter being preferably locked to the shaft 22, as for example, by the setscrew 41^a. The positive driving of the roll 53 is thus assured.

The "back" roll, hereinbefore generally designated at 24 (see Figure 2) and the upper or movable roll, hereinbefore designated at 28 (see Figure 2) are preferably of similar construction in so far as the

projections thereon are concerned. In Figures 5 and 6 is shown a preferred embodiment of the construction for these rolls. In these figures it will be noted that throughout the periphery of the cylindrical roll proper 53, the latter is milled out to provide a plurality of preferably axially extending recesses 53^c. These recesses 53^c may conveniently extend throughout the length 10 of the roll proper 53 and may be uniformly distributed throughout the periphery as indicated in Figure 6.

Seated within the recesses 53^c and spaced alternately one from another both in an 15 axial direction and a peripheral direction (see Figure 1) are a plurality of projecting members 54, known also as "lags." These lags 54 are preferably formed of a non-corrosive, non-absorbent fibrous material, and a preferred material known as "mimicarta." This material comprises fabric as 20 a base, is suitably chemically bonded and is waterproof. It is relatively rigid, and like the roll proper 53 is non-absorbent of the dyes. It possesses, however, the requisite qualities necessary for efficient felting action, as will be more clearly set forth hereinafter.

In so far as the back roll and the upper 30 roll are concerned, the lags 54 are fitted or seated in the recesses 53^c and are provided with under-cut end portions 54^a (see Figure 5) at which portions the lags 54 are secured to the roll proper 53 as by means of the screws 55. The lags 54, in being thus seated in their respective recesses are well supported against thrusts exerted thereon and transversely thereto during their operation, and it will be noted that the individual lags 40 are readily detached in order that replacements thereon, due to wear, for example, may be readily made.

Considering now the "front" roll, and hereinbefore designated at 23 (see Figures 45 1 and 2), the roll proper 23 (see also Figure 7) is preferably made up of a hollow metallic member having the same characteristics as the roll proper 53 hereinbefore described in connection with Figures 5 and 6. The recesses in the outer surface of the roll 50 base 23, however, extend peripherally for receiving the projecting members, and preferably form a continuous spirally arranged recess 23^a extending from one end of the roll base 23 to the other as will be clear from a consideration of Figure 1. The projecting parts of the front roll comprise preferably arcuate sections, preferably each of 180° in angular extent, and in Figure 7 60 is shown one of these sections at 56. These projecting members are made of a material having the same characteristics hereinbefore described in connection with the lags 54 of the back and upper rolls.

Each section 56 is under-cut as at 56^a at

the upper portion of one end thereof and as at 56^b at the under portion of the other end thereof. Adjacent sections such as 56 and 57, for example, (Figure 7) thus overlap one another and through these overlapping under-cut portions of adjacent sections is passed a suitable securing device, taking the form preferably of a suitably countersunk screw 58 threaded into the roll proper 23. Each section moreover is seated in its respective portion of the spiral recess, and is thus well supported against thrusts exerted thereon and in a direction transversely thereto. It will also be noted that that the projecting members 56, 57, etc., 75 overlap one another at their adjacent ends, and may be individually replaced at will.

Before taking up in detail the action of the apparatus, it will be noted that the upper roll 28, in being mounted in the movable auxiliary frame, may be moved toward or away from the remaining rolls in order to permit the insertion therebetween of the bundle of hats and the application thereto of the requisite rolling pressures. The spaced members 30 and 31 are extended forwardly at their upper ends as at 30^a and 31^a respectively, and in order to secure added rigidity to the movable auxiliary frame, the upper forward ends 30^a and 31^a are rigidly 80 connected together by a transversely extending brace 59 which preferably takes the form of a tubular member made up of two sections 59^a and 59^b, each threaded at one end thereof into suitably formed bosses at the ends of the members 30^a and 31^a, as is clearly shown in Figure 1. The two sections 59^a and 59^b are rigidly connected at their spaced adjacent ends by means of a sleeve member 60, cut away centrally at its forward portion (see Figures 1 and 2) as at 60^a, for a purpose more clearly hereinafter described. The sleeve number 60 has integrally formed therewith a handle portion 61, and the respective ends of the sleeve member 60 are rigidly secured to the tubular sections 59^a and 59^b as by set-screws 62 (see Figure 2) thus permitting the handle 61 to be adjustably positioned at the most convenient angle for manually controlling the 105 movement of the auxiliary frame and hence of the roll 28.

Mounted within the tubular connecting brace 59 and for relative rotary movement with respect thereto, is an operating rod 63 (see Figures 1 and 2) extending beyond the upper ends 30^a and 31^a of the spaced roll supporting members 30 and 31 respectively. At these outer ends of the rod 63 are rigidly mounted the pawls 64 and 65, each provided with an engaging tooth-like member 66, and adapted to coact with the toothed racks 67 and 68 respectively. These toothed racks are substantially arcuate in shape, and the center of the arc formed thereby is sub- 110 115 120 125 130

stantially coincident with the axis about which the movable frame is pivoted. The racks 67 and 68 are rigidly secured at their lower ends to the front upper ends of the standards 11 and 10 respectively, as by means of the bolts 69, and it will be noted that the racks are substantially coincident with the locus of movement of the upper ends of the movable frame.

- 10 A spring 70 (see Figure 2) connects the lower ends of the pawls 64 and 65 to the spaced members 30^a and 31^a and tends to hold the engaging member 66 of the pawls in engagement with their respective racks.
- 15 A handle member 71 is rigidly connected to the operating rod 63 intermediate of the tubular sections 59^a and 59^b and projects outwardly through the cut-away portion 60^a of the sleeve member 60, and is normally slightly spaced from the handle portion 61 (see Figure 2).

By means of the handle 61—71, the relation of the upper roll 28 to the remaining rolls may be positively and accurately controlled, it being noted that the handle means is preferably positioned, as shown in Figure 1, adjacent the right-hand end of the apparatus. The movable frame may thus be moved to carry the upper roll 28 toward or away from the remaining rolls to any desired extent. Before describing in detail the action of the locking devices for holding the movable roll in position, it may be pointed out that the bundle of hats operated upon must be subjected to a pressure dependent upon various factors, such as, for example, the quality of the material operated upon, the degree of extent to which the material or hats have already been sized or shrunk, etc. Upon having inserted the bundle of hats in the supporting trough formed by the lower rolls, the operator, by grasping the handle portion 61, may move the upper roll 28 downwardly to subject the bundle of hats to the desired degree of pressure. It is particularly to be noted that a single unidirectional manual movement suffices to bring this about, inasmuch as the pawls 64 and 65 automatically lock the roll 28 into whatever position it has been moved. The operator is thus relieved of the necessity of locking the movable roll in position by a separate manual movement, and he may thus devote his attention exclusively to the delicate materials operated upon.

Upon the bundle of hats having been subjected to the desired degree of rolling action by the rolls, they may thereupon be removed from the apparatus. The operator thus grasps the handle means 71—61 and with the same movement in the direction in which it is desired to move the movable roll 28 (in this case, away from the remaining rolls) swings the handle portion 71 in clockwise direction (as viewed in Figure 2) and the

initial movement thus imparted to it swings the operating rod 63 and with it the pawls 64 and 65 thus disengaging the latter from their respective racks. The continued movement thereupon swings the auxiliary frame member 30^a—31^a in a direction to move the roll 28 away from the remaining rolls to permit the removal of the bundle of hats. Here also it is to be noted that a single unidirectional manual movement suffices first, to unlock the roll, and secondly, to move the roll in the desired direction.

In order to assist in the movement of the roll 28 away from the remaining rolls, and thus to relieve the operator of undue physical effort, a spring 72 (see Figure 2) connects the movable frame to a stationary part of the apparatus. This spring 72 thus acts to tend to move the roll 28 away from the remaining rolls and thus assist the manual operation thereof by the operator. Reference to Figure 2 will indicate that the movable roll 28 may be moved in clockwise direction about the axis of the shaft 22 to such an extent that it may be placed to the right of the vertical plane through this axis and thus hold the roll 28 in "open" position, but the spring 72 is preferably employed to assist the clockwise movement of the roll 28 and to hold it in open position.

The spring 72 is connected at its one end through a pin 73 to one of the spaced frame members as the member 31. At its other end the spring 72 is connected to an arm 74 which is rigidly, but adjustably secured to the main frame. The main frame, or one of the standards, as the standard 11, is provided with a vertically projecting lug 75 (see now Figure 8) both faces of which are toothed as at 75^a. One face of the inner end of the arm 74 is likewise toothed as at 74^a, this toothed portion being adapted to interfit with the toothed portion 75^a of the lug 75. A bolt 76 clamps these parts in interfitting engagement and it will be noted that by loosening up the bolt 76 the arm 74 may be angularly displaced with respect to the axis of the bolt 76, thereby to vary the retractive effort of the spring 72. The action of the latter may thus be readily adjusted preferably to substantially counter-balance the movable frame and roll 28, or to contribute materially to the reverse movement of the movable frame and roll 28.

Against the other side face of the lug 75 and interposed between the head of the bolt 76 and this other face of the lug 75, is positioned a stop arm 77 (see also Figure 2) in substantial alignment with one of the members of the movable frame as the side member 31. The stop arm 77 is squared off at its lower end, as at 77^a to rest against the upper face of the standard 11, and thus is prevented from rotating about the bolt 76. It will thus be noted that the operator may,

at will, predetermine the degree of action of the spring 72, and that the stop arm 77 limits the retrograde movement of the movable frame with its roll 28.

5 Considering now more specifically the action of the apparatus upon the bundle of hats, it may first of all be noted, as hereinbefore set forth, the bundle of hats is of peculiarly irregular shape, and that the movable roll is subjected to non-uniformly distributed reactions. These irregular reactions upon the roll 28, which as also above noted, detrimentally affect the movable frame as well as the rotatable support for the movable 10 roll 28, are substantially nullified and the resultant disadvantages avoided in that the movable roll 28 and its supporting frame is positively locked in pressure-applying position by the spaced locking devices 65-68 15 and 64-67. Aside from the rigidity of the movable frame, as well as the rigidity of the rotatable support for the movable roll 28, the latter parts are thus effectively locked in pressure-applying position, and twisting 20 or torsion effects upon the frame and roll shaft are effectively avoided. The desired uniformity of rolling action of the co-operating rolls is thus consistently maintained throughout the action of the apparatus, uniform 25 felting is achieved, and unequal wear on the several coacting parts avoided.

In some cases, it may be desirable to have the movable roll 20 act yieldingly upon the work and I therefore and preferably give the 30 pawl 64 and 65 the form shown in cross section in Figure 3. In this figure it will be noted that the pawl member comprises a main body portion 78 rigidly secured to the operating rod 63, the main body portion 78 being bored out as at 78^a to receive slidably 35 therein a cylindrical plunger 79 carrying at its extreme lower end the engaging member 79^a for coaction with the rack or ratchet with which the pawl member is associated. 40 At the upper end of the main body portion 78, the latter is bored out as at 78^b to a greater extent in order to receive therein and about the plunger 79, a spring 80 reacting against the end wall of the recess 78^b and 45 against a nut 79^b at the upper end of the plunger 79. The spring thus tends to hold the parts in the position shown in Figure 3, and, it will be noted, permits the engaging member 79^a with associated plunger 79 to 50 yield relative to the operating rod 63 and a movable frame. With both pawl members 64 and 65 constructed in this manner, the yielding action of the movable frame and roll 28 is equalized at the respective ends 55 thereof, and these parts may yield with respect to the remaining rolls while maintaining the parts in proper alignment in order to achieve the advantages above noted.

The rolls are thus effectively maintained 60 in condition for consistent uniform action and for uniform wear thereof, and, in employing the preferred construction for the rolls and the projecting parts thereon, as hereinbefore described, the hat bodies may be sized or felted after dyeing, and the requisite 70 uniform shrinking or felting action after dyeing achieved so that the resultant hat body, after shrinkage, is maintained of uniform color throughout. In this connection it might be noted that the "micarta" material preferably employed for the projecting parts of the rolls, is not only non-absorbent of the color or dyes (and thus permit successive operations upon differently colored hat bodies) but also is exceedingly effective 75 in bringing about a high degree of kneading or felting action. The material of the projections permits the latter to effectively grip portions of the parts operated upon and thus positively move such portions relative to 80 other portions, bringing about a highly efficient kneading or felting action. Moreover, this efficient kneading action is maintained uniform throughout, in an exceedingly simple and effective manner which also contributes materially to the simple manual operation of the apparatus and its durability of construction and reliability of continued action.

As hereinbefore noted, the vat 90, which for simplicity of construction, may be made of wood and thereupon lined with a suitable non-absorbent material such as the sheet metal lining 91, prevents the different colors of various successive lots of hat bodies from 85 affecting one another; and, bearing in mind the kneading action of the rolls, I prefer to form in the outer or effective contacting surfaces of the spirally arranged projections or lags a series of transversely extending 90 grooves, shown at 93, in Figure 10, in connection with the fragmentary perspective view of the roll proper 23 and the spiral projections 92 thereon. The effective contacting surface of the spirally arranged lags is thus 95 broken up, providing not only an inherent kneading action in the lag itself as distinguished from the kneading action of the lag in its entirety, but also insuring a more effective grip upon the bundle of hat bodies. A 100 relative movement between contacting or overlapping fabrics is thus insured and the felting together of contacting fabrics of the hat bodies is effectively prevented.

The advantages attendant upon sizing the 105 hat bodies after they have been dyed have hereinbefore been briefly referred to. A distinctive feature of my invention, however, resides in the conjoint or simultaneous dyeing and sizing of the hat bodies. The solution 110 carrying the color or dye therein is placed directly in the vat 90, maintained at the required high temperature in any suitable manner, and may have added to it any of the 115 usually employed chemicals or other solu- 120

tions usually employed to make the felting or sizing action more rapid, and the like. The hat bodies, after having been "formed" have, as hereinbefore noted, a very soft and loose texture and the fibers of the fabric are merely sufficiently interlocked to maintain the integrity of structure of the hat body. As hereinbefore noted also, the hat bodies in this condition may be much more readily 10 and uniformly dyed. When, however, the hat bodies in this condition are taken directly to the sizing or felting machine, and subjected simultaneously to the coloring or dyeing of the solution in the vat and to the 15 felting action of the rolls, a much more efficient dyeing operation is brought about. The dye or color may not only thoroughly penetrate and affect all of the relatively loose fibers of the material, but, as the kneading 20 action proceeds, is also positively and reliably worked into the texture of the fabric and thus uniformly and positively is made to affect all of the fibers of the hat body or bodies. Thus the time, as well as the distinct 25 and separate step of dyeing, is eliminated while at the same time more beneficial and advantageous results are achieved. As the shrinking of the fabric proceeds, bearing in 30 mind the desirability of maintaining uniformity of kneading action as hereinbefore set forth, because of the dye, the desired felting or sizing of the hat bodies together with the thorough dyeing of the fibers in a uniform manner is achieved.

35 It will be noted that the above advantages are successfully achieved in addition to the advantage that the condition of the apparatus after operation thereon by one color or dye is such as to be in readiness for operation 40 with a dye of another color and that subsequent or successive operations with different colors are prevented from detrimentally and mutually affecting one another.

45 It will thus be seen that there has been provided in this invention a hat sizing apparatus in which the several objects of this invention, as well as many thoroughly practical advantages are achieved. It will be seen that the apparatus is of highly efficient 50 action, and that hat bodies may be felted or sized after dyeing thus achieving the important practical advantages attendant upon dyeing hats prior to the secure interfelting of the fibers thereof and that the disadvantages 55 attendant upon dyeing hats after the material thereof has been solidly interfelted are effectively avoided. It will also be seen that this invention, in providing for the simultaneous dyeing and sizing of the hat bodies, achieves still greater or more important 60 practical advantages than those hereinabove noted. It may moreover be noted that the consistent uniform action of the apparatus contributes materially to the achievement 65 of these and other important advan-

tages. It may also be pointed out that the apparatus is of simple manual control and thus reduces to a minimum the attention which the operator must give to the apparatus and its control and permits the operator 70 to devote substantially his entire attention and skill to the hat bodies undergoing the felting or sizing operation.

75 As many possible embodiments may be made of the above invention and as many changes might be made in the embodiment above set forth, it is to be understood that all matter hereinbefore set forth is to be interpreted as illustrative and not in a limiting sense.

80 I claim as my invention:

1. In apparatus of the character described, in combination, a plurality of rotatable sizing rolls, means mounting one of said rolls to permit it to be moved toward or away from the other rolls, a pawl and ratchet mechanism for holding said movable roll in said position when moved in one direction relative to the other rolls, and means for moving said movable roll in the other direction, said means being effective upon an initial movement thereof to disengage said pawl and ratchet mechanism.

85 2. In apparatus of the character described, in combination, a plurality of rotatable sizing rolls, means mounting one of said rolls to permit it to be moved toward or away from the other rolls, a mechanism for locking said movable roll in position when moved toward the other rolls, means for moving said movable roll away from the other rolls, said means including a handle member mounted upon said roll mounting means but movable relative thereto, and means responsive upon a relative movement of said handle member 90 with respect to said roll mounting means for releasing said locking means.

95 3. In apparatus of the character described, in combination, a plurality of rotatable sizing rolls, means mounting one of said rolls to permit it to be moved toward or away from the other rolls, a mechanism for locking said movable roll in position when moved toward the other rolls, and means for moving said roll away from the other rolls, said 100 means including a movable handle member adapted upon an initial movement thereof in a general direction away from the other rolls to release said locking means and upon continued movement to move said roll away 105 from the other rolls.

110 4. In apparatus of the character described, in combination, a plurality of rotatable sizing rolls, means mounting one of said rolls to permit it to be moved toward or away from the other rolls, a pawl and ratchet mechanism for holding said movable roll in the position into which it is moved in one direction relative to the other rolls, and handle means associated with said roll 115 120

- mounting means arranged and adapted to permit inter-engaging actuation of said pawl and ratchet mechanism when force is applied thereto to move said roll in one direction and to release said pawl and ratchet mechanism when force is applied thereto to move said roll in the other direction. 5. In apparatus of the character described, in combination, a plurality of rotatable sizing rolls, means mounting one of said rolls to permit it to be moved toward or away from the other rolls, a pawl and ratchet mechanism for holding said movable roll in the position into which it is moved in one direction relative to the other rolls, yieldable means connecting one member of said pawl and ratchet mechanism to said roll mounting means, and handle means associated with said roll mounting means arranged and adapted to permit inter-engaging actuation of said pawl and ratchet mechanism when force is applied thereto to move said roll in one direction and to release said pawl and ratchet mechanism when force is applied thereto to move said roll in the other direction. 6. In apparatus of the character described, in combination, a plurality of rotatable sizing rolls, a pair of spaced movable members in which one of said rolls is journaled and adapted to permit movement of said roll toward or away from the other rolls, a tubular member connecting said spaced members, locking mechanism coacting with one of said spaced members for locking said movable roll in position upon movement thereof, handle means for moving said spaced members, and means controlled by said handle means and mounted for guiding movement within said tubular member for releasing said locking mechanism. 7. In apparatus of the character described, in combination, a plurality of rotatable sizing rolls, a pair of spaced movable members in which one of said rolls is journaled and adapted to permit movement of said roll toward or away from the other rolls, a tubular member connecting said spaced members, locking mechanism coacting with one of said spaced members for locking said movable roll in position upon movement thereof, handle means for moving said spaced members including a handle portion rigidly mounted upon said tubular member and a coacting handle portion associated therewith but relatively movable with respect thereto, and means passing through said tubular member and responsive to the relative movement of said one handle portion with respect to the other for releasing said locking means. 8. In apparatus of the character described, in combination, a plurality of rotatable sizing rolls, a pair of spaced movable members in which one of said rolls is journaled and adapted to permit movement of said roll toward or away from the other rolls, a tubular member connecting said spaced members, a toothed member relative to which said spaced members are movable, a pawl movable with said spaced members and adapted to coact with said toothed member for holding said movable roll in the position into which it is moved with respect to the other rolls, a manually controlled means mounted for rotary displacement within said tubular member for controlling the coaction of said pawl with said toothed member. 9. In apparatus of the character described, in combination, a plurality of rotatable sizing rolls, a pair of spaced movable members in which one of said rolls is journaled and adapted to permit movement of said roll toward or away from the other rolls, a tubular member connecting said spaced members, a rod passing through said tubular member and mounted with respect thereto to permit rotary displacement thereof, a toothed member relative to which said spaced members are movable and a pawl coacting therewith for locking said spaced members in the position into which they are moved, said pawl being mounted to be moved into or out of engagement with said toothed member in accordance with the direction of the rotary displacement of said rod. 10. In apparatus of the character described, in combination, a plurality of rotatable sizing rolls, a pair of spaced movable members in which one of said rolls is journaled and adapted to permit movement of said roll toward or away from the other rolls, means associated with each of said spaced members adapted automatically to lock said roll in position upon movement thereof in one direction relative to said other roll, and means effective upon movement in the other direction adapted first to release said locking means and then to move said spaced members and said roll in the other direction. 11. In apparatus of the character described, in combination, a plurality of rotatable sizing rolls, a pair of spaced movable members in which one of said rolls is journaled and adapted to permit movement of said roll toward or away from the other rolls, means associated with each of said spaced members adapted automatically to lock said roll in position upon movement thereof in one direction relative to said other roll, a handle associated with said pair of spaced members for manually moving said members and said roll and mounted for limited movement with respect thereto in the other direction relative to said other rolls, and means responsive to said limited relative movement between said handle and

- said members for releasing said automatic locking means.
12. In apparatus of the character described, in combination, a plurality of rotatable sizing rolls, a pair of spaced movable members in which one of said rolls is journaled and adapted to permit movement of said roll toward or away from the other rolls, means associated with each of said spaced members adapted automatically to lock said roll in position upon movement thereof in one direction relative to said other roll, and manually controlled means movably mounted within said tubular member for releasing both of said locking means. 70
13. In apparatus of the character described, in combination, a plurality of rotatable sizing rolls, a pair of spaced movable members in which one of said rolls is journaled and adapted to permit movement of said roll toward or away from the other rolls, means associated with each of said spaced members adapted automatically to lock said roll in position upon movement thereof in one direction relative to said other roll, and a tubular member for rigidly connecting said spaced members, handle means for moving said movable roll including a handle portion rigidly mounted upon said tubular member and a second handle portion associated therewith, but relatively movable with respect thereto, and means passing through said tubular member and toward each end thereof adapted to be responsive to the relative movement of said second handle portion for releasing both of said locking means. 80
14. In apparatus of the character described, in combination, a plurality of rotatable sizing rolls, a pair of spaced movable members in which one of said rolls is journaled and adapted to permit movement of said roll toward or away from the other rolls, a transversely extending brace for rigidly connecting said two spaced members, locking mechanism for locking said movable roll in position upon movement thereof, and manually controlled means movably mounted co-axially with said brace for releasing said locking mechanism. 90
15. In apparatus of the character described, in combination, a plurality of rotatable sizing rolls, a pair of spaced movable members in which one of said rolls is journaled and adapted to permit movement of said roll toward or away from the other rolls, a transversely extending brace for rigidly connecting said two spaced members, locking mechanism for locking said movable roll in position upon movement thereof, and manually controlled means mounted lengthwise of said brace and movable with respect thereto for releasing said locking mechanism. 100

- scribed, in combination, a plurality of rotatable sizing rolls, a pair of spaced movable members in which one of said rolls is journaled and adapted to permit movement of said roll toward or away from the other rolls, a transversely extending brace for rigidly connecting said two spaced members, locking mechanism for locking said movable roll in position upon movement thereof, handle means for moving said movable roll comprising two parts, one of which is rigidly mounted upon said connecting means and the other of which is movable with respect thereto, and means responsive to the relative movement of said second part of said handle means for actuating said two pawl members. 130
17. In apparatus of the character described, in combination, a plurality of rotatable sizing rolls, a pair of spaced movable members in which one of said rolls is journaled and adapted to permit movement of said roll toward or away from the other rolls, means for rigidly connecting said two spaced members, a member relative to which said spaced members are movable having a series of recesses adjacent each of said spaced members and extending in the direction of movement thereof, a pawl member on each of said spaced members, each pawl adapted to coact with one of said recessed members for holding said spaced members in position upon movement thereof, and common means for actuating two said pawls. 140
18. In apparatus of the character described, in combination, a plurality of rotatable sizing rolls, a pair of spaced movable members in which one of said rolls is journaled and adapted to permit movement of said roll toward or away from the other rolls, means for rigidly connecting said two spaced members, a member relative to which said spaced members are movable having a series of recesses adjacent each of said spaced members and extending in the direction of movement thereof, a pawl member on each of said spaced members, each pawl adapted to coact with one of said recessed members for holding said spaced members in position upon movement thereof, handle means for moving said movable roll comprising two parts, one of which is rigidly mounted upon said connecting means and the other of which is movable with respect thereto, and means responsive to the relative movement of said second part of said handle means for actuating said two pawl members. 150
19. In apparatus of the character described, in combination, a plurality of rotatable sizing rolls, a pair of pivotally supported spaced arms in which one of said rolls is journaled and adapted upon movement thereof about their respective pivotal supports to carry said rolls supported thereby toward or away from the other rolls, an 160

- arcuate toothed member relative to which said movable arms are movable and mounted with respect thereto so that the center of said arcuate member is substantially coincident with the pivot about which said arms swing, and a manually controlled member carried by one of said arms and adapted to coact with said toothed member for holding said movable roll in the position into which it is moved. 5
20. In apparatus of the character described, in combination, a plurality of rotatable sizing rolls, a pair of spaced arms in which one of said rolls is journaled and 15 pivotally mounted to permit movement of said roll toward or away from the other rolls about the pivotal support of said arms, a pair of arcuate recessed members rigidly mounted and relative to which said arms 20 are movable positioned with respect to said arms so that the center of said arcuate members is substantially coincident with the pivotal support of said arms, and a pair of manually controlled members, connected one 25 with each of said arms and movable therewith, adapted to engage said recessed members respectively, thereby to hold said movable roll in the position into which it is moved. 30
21. In apparatus of the character described, in combination, a plurality of rotatable sizing rolls, a pair of spaced movable members in which one of said rolls is journaled and adapted to permit movement of 35 said roll toward or away from the other rolls, a pair of locking mechanisms, one for each of said spaced movable members, each comprising a member relative to which said spaced movable members are movable and 40 an engaging member for coaction therewith and movable with said movable roll for holding the latter in the position into which it is moved, and a manually controlled member rotatably mounted in said spaced movable members and adapted upon rotary movement thereof to control the coaction of said engaging members with said fixed members. 45
22. In apparatus of the character described, in combination, a plurality of rotatable sizing rolls, means mounting one of 50 said rolls to permit it to be moved toward or away from the other rolls, means for holding said movable roll in position when moved in one direction with respect to said other rolls, means for urging said roll in the other direction comprising a spring connected at one end thereof to said roll mounting means, an arm fixedly pivoted at one 55 end and connected at its other end to the other end of said spring, and means for adjustably positioning said arm about its pivot to vary the tension of said spring. 60
23. In apparatus of the character described, in combination, a plurality of ro- 65
- tatable sizing rolls, means mounting one of said rolls to permit it to be moved toward or away from the other rolls, means for holding said movable roll in position when moved in one direction with respect to said other rolls, means for urging said roll in the other direction comprising a spring connected at one end thereof to said roll mounting means, an arm having secured at its one end the other end of said spring, and means mounting said arm to permit it to be adjustably positioned to vary the tension of said spring. 70
24. In apparatus of the character described, in combination, a plurality of rotatable sizing rolls, means mounting one of said rolls to permit it to be moved toward or away from the other rolls, means for holding said movable roll in position when moved in one direction with respect to said other rolls, means for urging said roll in the other direction comprising a spring connected at one end thereof to said roll mounting means, a toothed member having secured thereto the other end of said spring, a rigidly positioned toothed member for coaction with said first mentioned toothed member, and means for holding said toothed members in interlocking relation in any desired position with respect to one another for adjusting the tension of said spring. 75
25. In apparatus of the character described, in combination, a plurality of rotatable sizing rolls, means mounting one of said rolls to permit it to be moved toward or away from the other rolls, means for holding said movable roll in position when moved in one direction with respect to said other rolls, means for urging said roll in the other direction comprising a spring connected at one end thereof to said roll mounting means, an arm having secured thereto at one end the other end of said spring and being formed at the other end to provide a gear-like hub, a fixed gear-like member, and means pivotally mounting said arm with respect to said fixed member adapted to permit said gear-like members to be locked together in any desired inter-engaging position thereof for adjusting the tension of said spring. 80
26. In apparatus of the character described, in combination, a plurality of rotatable sizing rolls, means mounting one of said rolls to permit it to be moved toward or away from the other rolls, and means for controlling the movement of said movable roll including a toothed stop member, a fixed toothed member with respect to which said toothed stop member may be adjustably positioned, and means for holding said toothed members in inter-engaging position. 85
27. In apparatus of the character described, in combination, a plurality of rotatable sizing rolls, means mounting one of 90

said rolls to permit it to be moved toward or away from the other rolls, and means for controlling the movement of said movable roll with respect to the other rolls including a stop arm shaped to provide a gear-like hub member, a fixed gear-like member with respect to which said stop arm may be adjustably swung, and means for holding said gear-like members in inter-engaging 10 position.

28. In apparatus of the character described, in combination, a plurality of rotatable sizing rolls, a pair of spaced movable members providing bearings in which 15 the shaft of one of said rolls is journalled and adapted to permit movement of said roll toward or away from the other rolls, a bushing surrounding said shaft and interposed therebetween and said bearing for 20 protecting said shaft against wear, and a pair of collars on said shaft, one on each side of said bushing, for clamping said bushing in position and to rotate with said shaft.

29. In apparatus of the character described, in combination, a plurality of rotatable sizing rolls, a pair of spaced movable members providing bearings in which the 25 shaft of one of said rolls is journalled and adapted to permit movement of said roll toward or away from the other rolls, a bushing on said shaft interposed therebetween and said bearing for protecting said shaft against wear, said bushing abutting against one end of the roll on said shaft, and means 30 for clamping said bushing against the end of said roll.

30. In apparatus of the character described, in combination, a plurality of rotatable sizing rolls, each having a driving 40 shaft, means mounting one of said rolls to permit it to be moved toward or away from the other rolls, journal means for supporting the shaft of one of said rolls, a bushing on said shaft interposed therebetween and 45 said journal means for protecting said shaft against wear, rigid means against which one end of said bushing abuts, means for clamping said bushing against said rigid means to insure its rotation with said shaft, and a 50 ball-bearing having its outer race supported in said journal means and having its inner race interposed between the other end of said bushing and said clamping means.

31. In apparatus of the character described, in combination, a plurality of rotatable sizing rolls, each having a driving 55 shaft, means mounting one of said rolls to permit it to be moved toward or away from the other rolls, journal means for supporting the shaft of one of said rolls, a bushing on 60 said shaft interposed therebetween and said journal means for protecting said shaft against wear, a collar on said shaft and against which one end of said bushing abuts,

means for clamping said bushing against 65 said collar, and a ball-bearing having its outer race supported by said journal means and having its inner race interposed between the other end of said bushing and said clamping means. 70

32. In apparatus of the character described, in combination, a plurality of rotatable sizing rolls, each having a driving shaft, means mounting one of said rolls to permit it to be moved toward or away from the other rolls, journal means for supporting the shaft of one of said rolls, a ball-bearing having its outer race supported by said journal means and having its inner race supported on said shaft, and means for enclosing said ball-bearing within said journal means. 75

33. In apparatus of the character described, in combination, a plurality of rotatable sizing rolls, a pair of spaced movable members in which one of said rolls is journalled and adapted to permit movement of one roll toward or away from the other rolls, means for moving said movable roll comprising a handle rigidly connected with said spaced movable members, and means mounting said handle with respect thereto, adapted to permit angular adjustment thereof with respect to the direction of movement of said movable roll. 80 90

34. In apparatus of the character described, in combination, a plurality of rotatable sizing rolls, a pair of spaced movable members in which one of said rolls is journalled and adapted to permit movement of one roll toward or away from the other rolls, a rigid member connecting said spaced movable members, a handle pivotally mounted upon said connecting member, and means mounting said handle thereon adapted to permit angular adjustment thereof about its pivot with respect to the direction of movement of said movable roll. 100 105

35. In apparatus of the character described, in combination, a plurality of rotatable sizing rolls, means mounting one of said rolls to permit it to be moved toward or away from the other rolls, and means forming projections on said rolls comprising a substantially rigid material capable of transmitting a substantial thrust without yielding, non-absorbent and having a fibrous composition so that its surface is capable of frictional holding when wet. 110 115

36. In apparatus of the character described, in combination, a plurality of rotatable sizing rolls, means mounting one of said rolls to permit it to be moved toward or away from the other rolls, each of said rolls being non-absorbent, and means forming projections upon each of said rolls comprising a substantially rigid material capable of transmitting a substantial thrust with- 120 125

out yielding, non-absorbent and having a fibrous composition so that its surface is capable of frictional holding when wet.

37. In a sizing machine for hat bodies, in combination, a cylindrical sizing roll, a shaft passing axially through said roll and projecting from the ends thereof, bearings in which the projecting ends of said shaft are rotatably supported, means for rotating said shaft, and a pair of metal members one at each end of said roll, each of said members comprising a metal plate secured to and covering the end of the roll, having a peripheral flange into which the end portion of the roll fits and a central opening through which said shaft passes, said opening being surrounded by a hub portion closely fitting said shaft and removably connected in driving relation with said shaft, said pair of metal members thus closing the ends of said roll against access of water or dye thereto and forming a driving connection between said shaft and said roll.

38. In apparatus of the character described, in combination, a sizing roll comprising a main body portion of a general cylindrical shape, a plurality of projecting members on said roll, each of said members being under-cut at its respective ends, and securing means passing through said under-cut portions of said projecting members.

39. In apparatus of the character described, in combination, a sizing roll comprising a main body portion of a general cylindrical shape, said main body portion being recessed at its outer surface, a plurality of projecting members seated within the recessed portions of said roll and under-cut at one end thereof, and securing means passing through the under-cut portion of said members.

40. In apparatus of the character described, in combination, a sizing roll, and projecting means thereon arranged spirally, said spiral means being in sections and arranged end to end, adjacent ends overlapping one another.

41. In apparatus of the character described, in combination, a sizing roll comprising a main body portion, spiral projecting means thereon comprising a plurality of sections arranged end to end and in overlapping relation at adjacent ends, and securing means therefor arranged at said overlapping adjacent ends.

42. In apparatus of the character described, in combination, a sizing roll comprising a main body portion having a spiral groove therein, projecting means seated within said groove and comprising a plurality of sections, each section being under-cut at its end, and means for securing said sections at the under-cut portions thereof to said main body portion.

43. In apparatus of the character described, in combination, a sizing roll comprising a main body portion having a spiral recess therein, projecting means seated within said recess and comprising a plurality of sections overlapping one another at adjacent ends, and means for securing said sections to said main body portion including means adapted to pass through the overlapping ends of said sections.

44. In apparatus of the character described, in combination, a plurality of rotatable sizing rolls, a pair of spaced movable members in which one of said rolls is journaled and adapted to permit movement of said roll toward or away from the other rolls, means for holding said spaced members in the position into which they are moved comprising a fixed member and an engaging member coacting therewith, and means mounting said engaging member to move with said pair of spaced members, said means including a connection adapted to permit said engaging member to yield with respect to said spaced movable members.

45. In apparatus of the character described, in combination, a plurality of rotatable sizing rolls, a pair of spaced movable members in which one of said rolls is journaled and adapted to permit movement of said roll toward or away from the other rolls, a rigidly positioned toothed member, a pawl movable with said spaced members and adapted to engage said toothed member to hold said movable roll in the position into which it is moved, and means mounting said pawl to be movable with said spaced members, said means including a connection adapted to permit said pawl to yield with respect to said spaced movable members.

In testimony whereof, I have signed my name to this specification this twentieth day of December, 1923.

GUSTAV S. BOESCH.
